Allis.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed March 8, 1921. Serial No. 450,741.

To all whom it may concern:

Be it known that I, FRED S. CARR, a citizen of the United States, and a resident of Newton, in the county of Middlesex, State 5 of Massachusetts, have invented an Improvement in Separable Fasteners, of which the following description, in connection with the accompanying drawings, is a specification, like characters on the drawings representing like parts.

This invention pertains to improvements in separable fasteners, and more particularly, though not exclusively, to separable fasteners adapted to be secured to carrying 15 fabrics by metallic securing means, such, for instance, as those ordinarily used in connection with glove fasteners and the like. It is among the objects of the invention to provide a fastener of superior holding power, 20 and simple and rugged construction, wherein in the socket element may be conveniently secured in a predetermined relationship to its carrying fabric by a socket-attaching tool.

25 In the drawings, which show a preferred form of one illustrative embodiment of my invention:—

Figure 1 is a front elevation showing a preferred form of stud and socket attached 30 to their carrying fabrics;

Fig. 2 is a section on the line 2—2 of Fig. 1; and

Fig. 3 is a section on the line 3—3 of Fig. 2.

35 Referring to the drawings and to the preferred form of my invention selected for illustrative purposes, I have shown a stud of the usual type including a head 4 and a neck 5, and secured to the stud-carrying 40 fabric 6 by a stud attaching rivet 7. The preferred form of socket illustrated includes a casing 8 containing a spring 9 and providing an outer flange 10 and an extension 11 adapted to pass through the socket-carrying 45 fabric 12 and to be clinched within a socket-securing cap 13. The spring 9 may be of the type illustrated in my co-pending application filed herewith, Serial No. 450,740, and may cooperate with the stud to provide a 50 lateral lock in the general manner described in said co-pending application. The spring 9 may be provided with a locating notch 20

on that side of the spring wherein the slit or slot 21 is located, this being, in the type of spring illustrated, the wider portion of 55 the annulus forming the spring. As in the co-pending application above referred to, means are provided for spacing the narrower side of the spring from the casing, the spacing means preferably, as illustrated, 60 taking the form of projections 22, 22' thrown up from the front flange 10 and adapted to engage faces 23, 23' on the springs so that lateral strain between stud and socket in the direction indicated by the arrow in Fig. 3 65 may tend to close the spring and increase the grip on the stud in the general manner described in the co-pending application above referred to. The notch 20 is, however, preferably distinct from the slit 21 in the spring. 70

While I have shown and described a preferred form of one embodiment of my invention, it will be understood that changes involving omission, substitution, alteration 75 and reversal of parts, and even changes in the mode of operation, may be made without departing from the scope of my invention, which is best defined in the following claims.

Claims.

1. A socket for separable fasteners including a casing, a sheet metal spring in said casing having a stud-receiving opening, said spring generally annular in peripheral shape but the annulus wider at one side of the stud-receiving aperture than at the opposite side thereof, said annulus split at the wider side thereof, means for spacing the narrower side of the spring from said casing and a locating notch communicating with the stud-receiving aperture but distinct 85 from the slit in the spring, said notch in the wider portion of said spring.

A socket for separable fasteners including a casing and a spring in said casing, said casing presenting spring retaining 95 flanges at each side of the spring and an extension from one of said flanges for securing the socket to its carrying fabric, the flange opposite said extension having projections engaging said spring to space said spring 100 away from one side of said casing.

In testimony whereof, I have signed my name to this specification.

FRED S. CARR.
